CLAIM

The ornamental design for a drifting kart, as shown and described.

DESCRIPTION

FIG. 1 is a perspective view of a drifting kart which embodies my design.

FIG. 2 is a left side view of the drifting kart of FIG. 1. The right side view of the drifting kart of FIG. 1 is the mirror image of FIG. 2, except the hand lever would be partially hidden behind the seat and the steering mechanism would be turned in the opposite direction.

FIG. 3 is a front view of the drifting kart of FIG. 1.

FIG. 4 is a rear view of the drifting kart of FIG. 1.

FIG. 5 is a top view of the drifting kart of FIG. 1; and,

FIG. 6 is a bottom view of the drifting kart of FIG. 1.

Broken lines are used to illustrate portions of the drifting kart which form no part of the claimed design.
